SHAKING AND DUMPING CRATE.

MANUFACTURED BY

CULTER & PROCTOR,

PEORIA, ILLINOIS.

UNITED STATES PATENT OFFICE.

RICHARD A. CULTER AND DAVID C. PROCTOR, OF PEORIA, ILLINOIS.

DESIGN FOR A STOVE.

Specification forming part of Design No. 6,972, dated November 4, 1873; application filed August 19, 1873.
[Term of Patent 7 years.]

To all whom it may concern:

Be it known that we, RICHARD A. CULTER and DAVID C. PROCTOR, of the city of Peoria, in the county of Peoria and in the State of Illinois, have invented a new Design for a Shaking and Dumping Heating-Stove, of which the following is a specification describing said design for a shaking dumping heating-stove.

The nature of our design is fully represented in the accompanying engraving, to which reference is made.

The general form of the stove is of (a common) egg shape, recurring at the parts at each end where the body meets the top or cap and the base, and has wide projecting moldings immediately above and below the central sliding doors, but no other moldings at any point between these and the cap and the base. The doors slide in opposite directions against and around the front surface of the stove, behind a vandyked guard exterior to the doors and at the base of the latter. The base of the stove containing the ash-pan is square, with rounded sloping corners, and slopes outward from the cavetto molding which forms its upper edge, down to a deepish recess in the surface of the broad bottom casting or hearth which receives the legs.

To be more explicit as to the combination of the moldings forming the configuration of the stove, we enumerate or name the moldings employed:

The cap commences with a cavetto and fillet lying upon a large ovolو, superimposed on a cyma reversa, which terminates in a pendent fascia, forming the extreme diameter of the cap. The retiring moldings from hence to the body are, in order, a large cyma recta, fillet and cavetto, ovolو, fascia, small ovolо.

The moldings above and below the doors have a general slope outward.

The foot-moldings are, in order, an ovolо connected by a fillet with a fascia below it per-

forated with elliptical air-holes, resting on an ovolо and fascia, which rests upon the ash-box, which is square.

The ash-box, containing the ash-pan, has a cavetto and fillet to form its upper edge; thence it descends at an angle of about ten degrees, terminating (on a plinth) in an apophyses and fillet. Said plinth finishes at its junction with the hearth (or flat casting which carries the legs) in an ovolо and cavetto, the latter rounding into the level broad recess of the surrounding flat hearth. From this recess to extremity of the hearth over the legs the moldings recede from the said flat horizontal recess by a cavetto, followed by an ovolо extending outward horizontally in a plain space, which drops, on its outer extremity, (which is also the extremity of the stove,) into a cyma reversa, under which molding, at the four corners, are placed the stove-legs. The ash-pan casting, which is attached to the sheet-iron pan, conforms to the face of the ash-box, into which it slides, and opens from the upper angle of ash-box to the foot of the plinth above the recess on the hearth.

We are aware that stoves of a similar, or of something like the general, configuration of this stove are not new; but we do not claim any particular feature of this stove alone; but

What we claim as our invention is—

The design for a heating-stove, consisting of the cap, with its several moldings, the egg-shaped body, and square base, as specified, and presenting an appearance substantially as shown in the accompanying illustration.

In testimony that we claim the foregoing design for a heating-stove we have hereunto set our hands this 11th day of August, 1873.

RICHARD A. CULTER,
DAVID C. PROCTOR.
